UMBRELLA

Clyde E. Clapper, Kansas City, Mo.

Application May 1, 1947, Serial No. 745,137

2 Claims. (Cl. 135—46)

1

The present invention relates in general to umbrellas and has for its primary objective the provision of an umbrella adapted to shade or shelter an area more or less removed from the main post or pedestal of the umbrella.

The post of a conventional umbrella falls at the center of the area of shelter, a fact which frequently reduces the usefulness of the area and hence of the umbrella. Suppose for instance it is desired to shade the operator of a tractor. With a conventional umbrella it is necessary to arrange a support for the umbrella post such that the post will be immediately adjacent to the tractor's seat in order to obtain as much benefit as possible from the umbrella. Even at best, of course, less than half of the umbrella can be over the worker; if it provides adequate shade when the tractor is going in one direction the umbrella very frequently is not properly located to give the desired shade when the tractor is turned in another direction. Moreover the close proximity of the umbrella post to the worker ordinarily interferes with one or more control operations which must be performed in the course of operating the tractor or its attachments.

With these facts in mind, it is an object of the present invention to provide an umbrella which has none of the shortcomings referred to above. More specifically, one object is to provide an umbrella wherein the supporting post or pedestal is near the edge of the sheltered area whereby the umbrella may be centered over the person or object to be sheltered while the post remains at a convenient distance therefrom.

Another object is to provide an umbrella of this type wherein the zone of shelter can be shifted easily with respect to the pedestal.

Another object is to provide an umbrella of improved construction which will be rugged and durable, yet simple and economical to manufacture.

Other objects and features will appear in the course of the following description of the invention. In the accompanying drawings which form a part of the specification and are to be read in conjunction therewith and in which like reference numerals are employed to identify like parts of the various views,

Fig. 1 is an elevational view showing my umbrella in raised position, the fabric covering having been omitted in the interest of clarity,

Fig. 2 is an elevational view corresponding to Fig. 1 but showing the umbrella in lowered condition,

Fig. 3 is an enlarged cross sectional view taken

2

along the line 3—3 of Fig. 1 in the direction of the arrows,

Fig. 4 is an enlarged sectional view taken along the line 4—4 of Fig. 1 in the direction of the arrows, and

Fig. 5 is an enlarged sectional view taken along the line 5—5 of Fig. 1 in the direction of the arrows.

Referring more particularly to the drawings, 10 my umbrella has a rigid post or pedestal 10 adapted to be mounted in a socket or held upright by any other suitable form of support, not shown. Pivoted on the upper end of the post are two spaced-apart arms 11 and 12 carrying at 15 their free ends a short extension post 13. The posts and arms form a parallelogram structure hinged at its corners (14) whereby the extension post 13 can swing up or down in an arc about the upper end of post 10 while at the same time remaining parallel thereto. As will be observed from Figs. 3 to 5, inclusive, each of the aforementioned arms comprise two bars disposed side by side and arranged to prevent sidewise tilting of the extension post.

25 In order to lock the extension post at any desired position in its arc, a collar 15 is provided which is connected to arm 12 by a link or brace 16. The brace is pivoted at its opposite ends to the arm and collar respectively, whereby the collar slides up and down post 10 as the extension post 13 moves in its arc. The downward movement of the collar is limited by a shoulder 17 on the post, and it may be rendered immovable in other positions by tightening a thumbscrew 18 against the post. This obviously locks extension post 13 in a fixed relationship to the main post 10.

The extension post has a fluted center section terminating in circular flanges or shoulders 20 and 21. A stud 22 projects upwardly from shoulder 20 and encircling this is a collar 23 which is maintained in fixed position thereon by a cotter key 24. The lower part of this collar comprises an annular channel adapted to retain a heavy wire 25 which is threaded through holes in the ends of the umbrella ribs 26, the sides of this channel being cut away at points opposite the ribs to permit said ribs to pivot up and down about the wire as a hinge.

Each rib is provided with a support or stay 28 having one end hinged to the associated rib at 29. At the opposite end the stays are hinged to a sleeve 30, the sleeve being provided with an annular channel adapted to retain wire 31 which is threaded through holes in the stays, as shown. 55 The inside diameter of the sleeve is just slightly

larger than shoulder 21 and the fluted part of the post 13.

When the umbrella is in its lowered position, sleeve 30 encircles the overlapping parts of arm 12 and brace 16 as shown in Fig. 2. This prevents arm 12 from pivoting downwardly even though the thumbscrew 18 is not tightened. When arms 11 and 12 are in the position shown in Fig. 2, a force may be applied by hand to the sleeve 30 causing it to slide up arm 12 and over shoulder 21. This, of course, through the medium of stays 28 elevates the ribs 26 so that the umbrella covering (not shown) assumes its conventional taut or "raised" condition. As sleeve 30 passes above shoulder 21 arms 11 and 12 are allowed to swing toward their Fig. 1 position thereupon the tips 32 of arm 12 engage the bottom of the sleeve 30 and prevent retrograde movement thereof.

To lower the umbrella it is necessary to return arms 11 and 12 all the way to their Fig. 2 position, for only then is it possible for sleeve 30 to pass downwardly over the joint between post 13 and arm 12. In other words, in all positions of the arms intermediate those shown in Fig. 1 and Fig. 2 the umbrella will remain up. Thus, the center of the raised umbrella may be displaced various distances from the axis of post 13 and this, together with the fact that the post is free to turn in its socket or support so that the umbrella center can move in a circle about the post as an axis, makes it possible to shade or shelter any selected portion of an area very much larger than the umbrella itself.

From the foregoing it will be seen that this invention is one well adapted to attain all of the ends and objects hereinbefore set forth, together with other advantages which are obvious and which are inherent to the apparatus.

Inasmuch as many possible embodiments of the invention may be made without departing from the scope thereof it is to be understood that all matters herein set forth or shown in the accompanying drawings is to be interpreted as illustrative and not in a limiting sense.

It also will be understood that certain features and subcombinations are of utility and may be employed without reference to other features and subcombinations. This is contemplated by and is within the scope of the claims.

Having thus described my invention, I claim:

1. An umbrella comprising a primary upright post, a secondary post, upper and lower arms having one end hinged to said secondary post at longitudinally spaced points and having the opposite end hinged to the upper portion of the pri-

mary post at longitudinally spaced points, whereby said secondary post is free to swing up and down in an arc about the upper end of said primary post while being maintained substantially parallel thereto, a sleeve normally encircling the lower one of said arms, said sleeve being slideable along said one arm and onto said secondary post when said one arm and secondary post are in substantial alignment, said sleeve resting on said one arm when said arm is in angular relationship to said secondary post to prevent retrograde movement of said sleeve, and said upper arm forming a stop to limit upward movement of the sleeve along said secondary post, fabric supporting ribs hingedly connected to said secondary post, and stays connecting the ribs to said sleeve whereby the ribs are raised to stretch the fabric taut when said sleeve encircles said secondary post.

2. An umbrella comprising a primary upright post, a secondary post, a pair of arms having one end hinged to said secondary post at longitudinally spaced points and having the opposite end hinged to the upper portion of the primary post at longitudinally spaced points, whereby said secondary post is free to swing up and down in an arc about the upper end of said primary post while being maintained substantially parallel thereto, a collar slidably mounted on one of said posts, a brace having one end hinged to the collar and the other hinged to one of said arms intermediate its ends, and means for securing said collar fixedly to said one post at different positions along the length of said post thereby to immobilize said secondary post in any selected position in said arc.

CLYDE E. CLAPPER.
